United States Patent

Des. 234,733

Patented Apr. 8, 1975

234,733

CORNER-MOUNTED HOLDER FOR TOILET TISSUE

Curtiss M. Peasley, 25 Boulder Drive,
Burlington, Mass. 01803

Filed Jan. 16, 1974, Ser. No. 433,813

Term of patent 14 years

Int. Cl. D23—02

U.S. Cl. D6—97

Fig. 4.

Fig. 3.

FIG. 1 is a perspective view showing the top, front and left-hand side of a corner-mounted holder for toilet tissue according to my new design;

FIG. 2 is a bottom view thereof;

FIG. 3 is a side elevational view showing the right-hand side thereof; and,

FIG. 4 is a front elevational view thereof.

I claim:

The ornamental design for a corner-mounted holder for toilet tissue, as shown and described.
